UNITED STATES PATENT OFFICE.

CHRISTOPHER MCRAE, OF SAN FRANCISCO, CALIFORNIA.

BROOM OR MOP HOLDER.

1,384,619.

Specification of Letters Patent. Patented July 12, 1921.

Application filed June 19, 1920. Serial No. 390,141.

To all whom it may concern:

Be it known that I, CHRISTOPHER MCRAE, citizen of the Dominion of Canada, residing at San Francisco, in the county of San Francisco and State of California, have invented new and useful Improvements in Broom or Mop Holders, of which the following is a specification.

This invention relates to improvements in 10 broom holders designed to be secured to a suitable fixture to removably support a broom or other similar articles.

The principal object of this invention is to provide a sure and effective clamping means 15 which can be readily brought into use for the purpose of clamping and holding the broom or other articles, and which can be disengaged with equal facility so as to release the articles when desired.

20 A further object of this invention is to provide a device of the above mentioned character, which is simple in construction, inexpensive to manufacture, strong, durable, and reliable in operation.

25 Other objects and advantages of this invention will be apparent during the course of the following description.

In the accompanying drawings forming a part of this specification and in which like 30 numerals are employed to designate like parts throughout the same,

Figure 1 is a front elevation of a broom holder constructed in accordance with my invention,

35 Fig. 2 is a side elevation of the invention illustrating the handle of a broom or mop held by the clamping element, and

Fig. 3 is a top plan view of my device.

In the accompanying drawings wherein 40 for the purpose of illustration is shown a preferred embodiment of my invention, B designates a bracket member comprising a body portion 4 which terminates at one end in a pair of lips 5, which are bent outwardly at a right angle with the plane of the body portion, and terminates at the opposite end in a pair of angular jaws 6, the extremities of the same being parallel with the plane of the body portion 4. It will be

45 noted that the pair of lips 5 are formed with openings for the reception of screws or other fastening means to secure the holder in place to a fixture.

50 As shown here, the bracket B is preferably formed of separable sections which are held in close engagement with each other by a

stud 7, although the bracket may be made of sheet metal and stamped in one piece.

Secured on the angular jaws 6, adjacent the extremities of the same, there is supported, upon a pivot 8, a concave roller or spool 9. This roller is mounted upon the jaws 6 at a point adjacent the periphery of the roller, which mounting allows the roller to be eccentrically positioned on the jaws 6. 65

The roller 9 has a concave surface formed thereon and has suitably attached to this concave surface a rubber covering 10 for the purpose of frictionally holding and clamping the handle 11 of the broom or mop supported between the roller 9 and a clamping ring or element 12. While the concave surface of the roller is here set forth as being provided with a rubber covering, it is to be noted that a roughened or serrated surface 75 may also be provided to accomplish the same result.

This clamping ring 12, above referred to, is of a circumference larger than the circumference of the broom handle to be inserted therein, and it will be noted that by providing this form of clamp I have set forth means for easily permitting various sizes of handles to be inserted in the clamping ring. The clamping ring 12 is pivoted at 13 to the roller 9 at 80 a point adjacent the edge thereof and serves as means for holding an article in position on the holder. It will be noted that since the roller 9 is provided with a concave surface, it will serve to accommodate the round 85 surface of a handle, and that the edges 14 and 15 of the concave surface will tend to hold the handle contacting with the surface against lateral displacement when an article is held in position, as shown in Fig. 2. The 90 combination of the roughened surface, the edges of the roller and the clamping element 12 will thus serve to hold securely the handle of the article until the user desires to release the same. 100

The operation of my device is as follows: When the handle of a broom or other article is inserted in the clamping ring and is raised to the desired height, the handle will contact with the roller and being released from the hand of the user will fit snugly in the concave surface of the roller. Thus a binding action takes place when the clamping ring presses tightly around the surface of the handle of the article. In order to release the handle 110 from the holder, all that is necessary is to move the handle upwardly and the roller

will move upon its pivot and thus allow free movement of the broom handle within the clamping ring and consequently the handle can be very easily released by withdrawing 5 the same from the clamping ring.

It is to be understood that the form of my invention herewith shown and described, is to be taken as a preferred example of the same, and that various changes in the shape, 10 size and arrangement of parts may be resorted to without departing from the spirit of the invention or the scope of the subjoined claims.

Having thus described my invention, I 15 claim:—

1. A device of the character described comprising a bracket member, a roller having a concave roughened surface and being pivoted to said bracket at a point adjacent the edge 20 thereof, said roller having edges formed by

the concave surface to prevent lateral displacement of an article resting thereon, and a clamping element attached to said roller and adapted to embrace the article inserted in the clamping element.

2. A device of the character described comprising a bracket member, said bracket member comprising separable sections, each section terminating in an angular lip at one end and an angular jaw at the opposite end thereof, a concave roller eccentrically pivoted to the jaws of said bracket member and provided with a roughened surface, and a clamping element attached to said roller at a point adjacent the outer edge thereof and adapted to embrace the article inserted in the clamping element.

In testimony whereof I affix my signature.

CHRISTOPHER McRAE.
